(57) **CLAIM**

I claim the ornamental design for a processor cooling pump cover, as shown and described.

DESCRIPTION

FIG. 1 is a front perspective view of the processor cooling pump cover comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a rear perspective view thereof; and,

FIG. 9 is a front perspective view of the processor cooling pump cover installed in an information handling system housing environment.

The broken lines on the claimed surfaces illustrate portions of the processor cooling pump cover. The remaining lines illustrate environment. The broken lines form no part of the claimed design.
